No. 805,120.

PATENTED NOV. 21, 1905.

M. CRIPPEN.

FOLLOWER FOR BARRELS, PICKLE JARS, &c.

APPLICATION FILED APR. 6, 1905.

UNITED STATES PATENT OFFICE.

MARTIN CRIPPEN, OF OLYPHANT, PENNSYLVANIA.

FOLLOWER FOR BARRELS, PICKLE-JARS, &c.

No. 805,120.

Specification of Letters Patent.

Patented Nov. 21, 1905.

Application filed April 6, 1905. Serial No. 254,245.

To all whom it may concern:

Be it known that I, MARTIN CRIPPEN, a citizen of the United States, residing at Olyphant, in the county of Lackawanna and State of Pennsylvania, have invented certain new and useful Improvements in Followers for Barrels, Pickle-Jars, &c.; and I do hereby declare the following to be a full, clear, and exact description of the same, reference being had to the accompanying drawings, forming a part of this specification, and to the letters of reference marked thereon.

The present invention relates to that class of device employed in pickle-jars and barrels of salt meat or kraut-barrels for holding the solid contents or articles to be pickled down beneath the surface of the brine or other liquid.

The objects of the invention are to provide a simple inexpensive form of device capable of use on practically all kinds of vessels, such as are used for preserving, pickling, or storing articles of the classes mentioned, which device shall be of such construction that the follower may be readily adjusted and held at any desired level in the vessel and at the same time be easily released and moved by one hand without requiring the manipulation of catches, set-screws, &c.

Primarily the invention consists in a cross-piece adapted to be engaged with the edges of the open end of the vessel in such manner as to resist upward movement, said cross-piece being provided centrally with a recess or open-sided slot adapted to coöperate with any one of a series of recesses and projections formed on the rod of a suitable follower.

The invention further consists in certain novel details of construction and combinations and arrangements of parts, all as will be now described, and pointed out particularly in the appended claims.

Referring to the accompanying drawings, Figure 1 is a perspective view of a pickle-jar equipped with devices embodying the present improvements. Fig. 2 is a vertical section through the same. Fig. 3 is a plan view of the plunger. Fig. 4 is a perspective view corresponding to Fig. 1, but showing the application of the invention to a barrel. Fig. 5 is a detail view of the retaining hoop or ring preferably employed in connection with a barrel or vessel having no bead or rim at the mouth. Fig. 6 is a detail plan view of a retaining cross-piece. Fig. 7 is a perspective

view of a modified form of retaining cross-piece.

Similar letters of reference in the several figures indicate like parts.

The pickle-jar A of Figs. 1 and 2 and the barrel B of Fig. 4 are both of ordinary or preferred types, the jar A being, as usual, provided with a bead or projecting rim *a* at the mouth. In accordance with the present invention I provide a retaining cross-piece C, which may be a simple strip of metal or a light casting, and in order to secure the same to the mouth of the vessel with a sufficient firmness the ends of the cross-piece are made hook-shaped at *c*, so as to pass around and engage the under side of the lip or rim *a*. Centrally of the cross-piece it is formed with a deep recess or open-sided slot, as at D, Fig. 6, the width of the notch or slot being such that a plunger-stem E may readily enter the same, but be held against longitudinal movement therein by suitable projections on the stem. In the preferred construction the plunger-stem E is provided with a series of annular recesses *e* and intermediate projections *e'*, the recesses and projections extending throughout a sufficient length of the stem to provide for the desired range of adjustment. The stem itself is preferably made of wood, as is also the plunger carried by it, no metallic connections being employed, inasmuch as metallic parts would be undesirable where the device is used as a retainer with certain kinds of liquid.

As a convenient means of forming and uniting the several parts constituting the follower and stem the said follower F is of hardwood, with suitable apertures *f* therethrough, and extending transversely of the grain of the wood is a dovetail wedge-shaped key F', which key will serve to hold the follower against warping and at the same time will increase its thickness at the center, so as to afford a firm base for the attachment of the stem. The stem is attached by having its reduced end E' passed through or driven into registering apertures in the key F' and follower F. Thus each serves to retain the other in place, and the connection may be made more secure, if so desired, by suitable wedges driven in the end of the stem, as is usual in attaching handles to tools of various kinds.

The retaining cross-piece C may, if desired, be provided with a strengthening flange or

rib C', and this flange or rib may extend only throughout the central portion of the cross-piece, where it is weakened by the cutting of the slot or recess D, or it may extend throughout the length of the cross-piece, if so desired.

When the device is intended for use in connection with a barrel or other receptacle having no lip or bead near its open end, a hoop or removable bead H, Figs. 4 and 5, may be provided, and this hoop or removable bead H is preferably formed of iron round in cross-section and with its ends adjustably connected together, as by a bolt h, thus adapting the device for use on receptacles of different size and at the same time providing a means whereby it may be firmly clamped in position so as to permit of the ready engagement of the cross-piece therewith.

The device described, it will be noted, is extremely simple and may be so cheaply and easily constructed that all of the desired sizes may be provided without material expense. Thus a merchant may keep on hand sizes adapted for all ordinary vessels.

25 The device is particularly convenient inasmuch as the follower and its stem constitute the only parts which need be lifted by those using the devices, and, furthermore, the user may with one hand disengage the follower from the cross-piece and lift it to the top of the vessel, so as to give access to the vessel for the insertion or removal of material. As in these manipulations one hand only is necessary, the other hand is left free for use in handling the material or articles to be removed or placed in the receptacle.

In the modification Fig. 7 a means is shown whereby the cross-piece may be adapted to vessels of various sizes, for which purpose 40 the ends of said cross-piece are made round and screw-threaded, as at S, for the reception of nuts S', having at one side hook-shaped projections S'', adapted to take under the bead or lip of the vessel. As a convenient construction the body of the cross-piece may be formed of iron rod having a semicircular bend T at the center and a spider-arm t, adapted to rest on the far side of the receptacle, so as to prevent the cross-piece from 45 rotating with the ends of the rod as an axis. A circular plate U may be secured centrally to the body of the cross-piece, and the recess

or open-sided slot for the reception of the plunger-stem may be formed in this circular plate, all as illustrated in the figure of the 55 drawings last above referred to.

Having thus described my invention, what I claim as new, and desire to secure by Letters Patent, is—

1. The combination with a receptacle, a 60 cross-piece arranged across the top thereof and having a central recess or open-sided slot extending into the cross-piece from one side, and means whereby said cross-piece may be secured to the mouth of the receptacle to resist upward movement, of a follower and a stem on said follower having a series of projections of greater width than the slot and a series of recesses of less width, adapted to coöperate with the slot or recess in the cross-piece whereby the follower will be held against longitudinal movement through the slot or recess in the cross-bar; substantially as described. 70

2. The combination with a receptacle, a 75 cross-piece arranged across the top thereof, said cross-piece having a central recess or open-sided slot extending into the cross-piece from one side and means whereby said cross-piece may be secured to the mouth of the 80 receptacle to resist upward movement, of a follower located in the receptacle and a follower-stem having alternately-arranged annular grooves and projections, said projections being of greater width than the slot in the 85 cross-piece and the recesses of less width, whereby the follower will be held against longitudinal movement, through the slot or recess; substantially as described.

3. In a device such as described the combination with the follower formed of wood and the dovetail key having a uniform taper from end to end, extending across the grain of the wood and which extends above the surface of the follower, whereby the thickness of the follower is increased at the center, of the follower-stem mounted in registering openings in the key and follower and means for holding the follower against longitudinal movement; substantially as described. 95

MARTIN CRIPPEN.
